UNITED STATES PATENT OFFICE

152,043

DESIGN FOR A BROILER BASE

Henry J. Talge, Kansas City, Mo., assignor to
 John C. Hockery, Kansas City, Mo., trustee for
 Henry J. Talge and Foster L. Talge

Application April 15, 1946, Serial No. 128,605

Term of patent 14 years

(Cl. D44—1)

To all whom it may concern:

Be it known that I, Henry J. Talge, a citizen of the United States, residing at Kansas City, in the county of Jackson and State of Missouri, have invented a new, original, and ornamental Design for a Broiler Base, of which the following is a specification, reference being had to the accompanying drawing, forming part thereof, in which

Fig. 1 is a perspective top view of a broiler base embodying my new design, and

Fig. 2 is an edge view taken from the well end of the broiler base shown in Fig. 1.

The characteristic feature of my design resides in the combination, on the broiler base disclosed, of the depressed fish and well pattern in the hammered bottom as shown.

I claim:

The ornamental design for a broiler base, substantially as shown and described.

HENRY J. TALGE.
